By Thos. C. Fullerton
Atty.

UNITED STATES PATENT OFFICE.

ROBERT H. BURWELL, OF BIRMINGHAM, ALABAMA, ASSIGNOR OF ONE-HALF TO E. K. FULTON AND PEYTON G. KING, OF SAME PLACE.

WAGON-HUB.

SPECIFICATION forming part of Letters Patent No. 247,798, dated October 4, 1881.

Application filed June 6, 1881. (No model.)

To all whom it may concern:

Be it known that I, ROBERT H. BURWELL, a citizen of the United States, residing at Birmingham, in the county of Jefferson and State 5 of Alabama, have invented certain new and useful Improvements in Wagon-Hubs; and I do hereby declare the following to be a full, clear, and exact description of the invention, such as will enable others skilled in the art to which it 10 appertains to make and use the same, reference being had to the accompanying drawings, and to the letters or figures of reference marked thereon, which form a part of this specification.

My invention relates to improvements in hubs 15 adapted to all kinds and styles of vehicles; and its objects are to furnish an article that combines a complete, compact, strong, and durable hub, and so adjusted in its several parts as to enable a common workman with ordinary tools 20 to repair with little expense a wheel by inserting new spokes and tightening the tire without being heated or taken from the wheel. I also claim that my invention will save most of the incipient wear and tear of a wheel by the timely 25 use of a hand-wrench. The nut E being virtually the key to the whole combination, an occasional turn of it will keep the spokes and all the parts of the hub firmly in their place, regardless of weather and ordinary exposure.

30 In the accompanying drawings, Figure 1 represents a sectional view of my invention at line y y in Fig. 2. Fig. 2 represents a sectional view at line x x in Fig. 1; Fig. 3, a view of the inner end, and Fig. 4 a view of the outside end.

35 A is a single block of wood, bored through the center to admit the axle-box D, its surface turned with shoulders at points indicated by A' A² at the inside end.

B is the spoke-band, with mortises combined and open toward the point end of the hub. It 40 is made of iron, and shrunk tightly upon the wooden part A and between the shoulders A' and A².

C is a band, also made of iron, with a shoulder, C', within its periphery, and made to fit closely 45 upon the wooden part A, and to press against the spokes and close the mortises at their open ends. It is bolted to part B and held in position by four screw-bolts, C².

D is the axle-box, made of cast-iron or steel, 50 and in one piece, with a square head, and threads and a square tap, E, at the point. Its diameter should equal that of the bore in the wooden part A, and its square head fit snugly into the socket, thus keeping its position and revolving 55 with the wheel. The tap E presses against the shoulder C', and when screwed up tight brings all the parts together compactly, and holds every spoke firmly in place.

What I claim as my invention, and desire to 60 secure by Letters Patent, is—

1. In a wagon-hub, the combination of the wooden part A, the spoke-band B, the band C, the screw-bolts C², the axle-box D, and screw-tap E, substantially as set forth and described. 65

2. In a hub for vehicles, the combination, with an axle-box, D, with a square head and thread and screw-tap, E, of the wooden part A, the spoke-band B, the band C, and the screw-bolts C², substantially as described. 70

In testimony whereof I affix my signature in presence of two witnesses.

ROBERT H. BURWELL.

Witnesses:

JOHN W. WHITE,
J. S. QUARLES.
